UNITED STATES PATENT OFFICE.

JAMES TINLIN, OF CLAPHAM, COUNTY OF SURREY, AND JULIAN J. PIATKOWSKI, OF GOSWELL ROAD, COUNTY OF MIDDLESEX, ASSIGNORS TO SILAS MAINEVILLE BURROUGHS AND HENRY SOLOMON WELLCOME, BOTH OF LONDON, ENGLAND.

MACHINE FOR COMPRESSING DRUGS.

SPECIFICATION forming part of Letters Patent No. 390,823, dated October 9, 1888.

Application filed December 27, 1887. Serial No. 239,097. (No model.) Patented in France November 24, 1887, No. 187,181; in Belgium November 24, 1887, No. 79,658; in England November 25, 1887, No. 16,239; in Sweden December 2, 1887, No. 606; in Norway December 5, 1887, No. 793; in Spain February 18, 1888, No. 7,694, and in Italy March 24, 1888, XLV, 290.

To all whom it may concern:

Be it known that we, JAMES TINLIN and JULIAN JOSEPH PIATKOWSKI, subjects, respectively, of the Queen of Great Britain and the Emperor of Austria, and residing at Kamballa Road, Clapham, in the county of Surrey, and Spencer Street, Goswell Road, in the county of Middlesex, England, have invented certain new and useful Improvements in Apparatus for Compressing Drugs and other Substances, (the same having been patented in England November 25, 1887, No. 16,239; in France November 24, 1887, No. 187,181; in Belgium November 24, 1887, No. 79,658; in Spain February 18, 1888, No. 7,694; in Italy March 24, 1888, No. 290, Vol. 45; in Sweden December 2, 1887, No. 606, and in Norway December 5, 1887, No. 793,) of which the following is a specification.

This invention relates to that class of apparatus which is employed for compressing drugs or other substances, the compression taking place in holes or recesses formed in a disk which is intermittently rotated in a horizontal plane.

The invention consists in an improved construction and arrangement of parts whereby the rate of production of the compressed goods is materially increased over that of similar machines previously known.

In order that the invention may be clearly understood, reference is made to the accompanying drawings, which form part of this specification, and in which—

Figure 1 represents a side elevation of the improved machine. Fig. 2 represents a rear end elevation. Fig. 3 represents a front end elevation. Fig. 4 represents a plan view of Fig. 1. Fig. 5 represents a plan view of the parts beneath the bed-plate. Fig. 6 represents, on a slightly larger scale, a plan view of the intermittently-rotated disk, some of the surrounding parts being in section. Fig. 7 represents, on a slightly larger scale, a side elevation, partly in section, of the lower lever

and eccentric which operates the compressing plungers or dies. Fig. 8 represents in side elevation the filler through which the goods to be compressed are fed to the holes in the disk. Fig. 9 is a plan view thereof; and Fig. 10 is an elevation, partly in section, of the guide for the top plunger or die.

In all the figures like letters of reference are used to indicate like parts of the apparatus.

The substances to be compressed are placed in the hopper A, from whence they pass to the filler A', and from there through the hole a to the holes a' in the intermittently-rotating disk B, the face of said disk being practically in contact with the bottom of filler A', so as to prevent the substance from the filler flowing out, except when the hole a coincides with one of those, a', in the disk, while beneath the disk is a fixed ring or plate, B', which prevents the substance falling through, said ring only being perforated for the plungers, hereinafter mentioned. The filler-case is loosely mounted in the supporting-piece A'', which also carries a feed-screw, a'', adapted to engage with the toothed edge of filler A', and thereby adjust the filler so as to bring hole a into or out of line, or partially in or partially out of line, with the travel of holes a', depending upon whether it is desired to feed the substance rapidly, slowly, or not at all.

When the filler has been set as desired, it is held in position by set-screw a''. The stirrers are preferably mounted on separate shafts b b', driven from shaft b'', which in turn is operated through pulley B', mounted thereon, and band b'', which is driven from a step-pulley, B'', on the main driving-shaft C. As both pulleys B' are stepped, the speed of rotation of the stirrers may be varied as desired, and the band b'' be adjusted by setting movable plate b', which carries the pulleys b'' b'', over which the band runs. A lever, D, pivoted at d, is given a horizontal reciprocating motion from eccentrically peripherally grooved drum E, with which the projecting end or pin d' of lever D

engages. The other end of said lever is connected by rod d^2 with slide F, which carries pivoted pawl f, which is held against the periphery of disk B by the spring f'. As the 5 slide-plate F moves forward, pawl f engages with the notched edge of the disk and partially rotates it, while at the end of the stroke one end of pivoted catch-lever G falls into a notch and prevents further movement until slide F 10 has returned to the end of its stroke and pawl f is ready to again partially rotate the disk, by which time pin f² has come into contact with the outer end of lever G, and, having overcome the action of spring g, has withdrawn 15 the catch. An additional catch formed by spring g' may be used, if desired. The compressing plungers or dies H H' are operated by levers H², pivoted on H³, the outer ends being actuated by eccentrics on main driving-shaft C. The top lever H² is represented as being operated by connecting-rod H⁴, terminating in two rings, h h, surrounding the two eccentrics. The lower lever H² is operated by a cam, I, with which a stud on said lever enters. By placing cam I between the eccentrics the top and bottom levers H² are kept in the same plane and are practically pivoted on the same post, H³, which, for convenience of construction, may be made in two parts, screwed 25 into the bed-plate and together, and held in position by lock-nuts, as most clearly shown in Fig. 7, in which the levers H² are represented as having a stroke or leverage of two to one, while in the rest of the figures it is indicated as being even.

The apparatus can of course be constructed with any given amount of leverage, depending upon the pressure and length of stroke it is desired to obtain. The plungers H H' are attached to the levers by toggle-joints h' h' and set-screws h² h², by which the distance apart of the plunger ends may be regulated. The plungers travel in guides H⁵, in which they are kept from rotating by feathers or screws h³, and are capable of slight adjustment by means of set-screws h⁴ h⁴, which carry the packing-ring h⁵. Eccentric J operates upon one end of lever J', pivoted at j, the other end of said lever being connected through rod J² 40 with plate J³, all side motion of which is prevented by guide-rod j'. Plate J³ carries plungers j² j³ j⁴, all being set in the line of travel of holes a' in the disk.

It being understood that all the parts are 55 driven from the main shaft C, the operation of the machine may be described as follows: The substance to be compressed passes from the hopper A to filler A', thence through hole a into the hole a' on the disk immediately beneath. The plungers all being up clear of the disk, slide-plate F begins its forward movement, the pawl f carrying the disk around until the catch on lever G falls into one of the notches, by which time the hole just filled has 60 come over plunger H' and under plunger H, which are then closing, and between the ends

of which the substance is compressed and left in the hole, the hole a' next in order at the same time being filled. As the plungers withdraw, the slide F again advances and the operation is repeated until the compressed substance comes under plunger j', which forces it from the hole into a suitable box or receptacle placed beneath the disk and bed-plate. At the next downward stroke of plate J³ the 75 plunger j' passes into the hole just emptied and cleanses it, and at the next stroke plunger j' greases or polishes the hole previous to its being again filled, the top of disk B being also cleaned by passing under wiper K, which 80 may be made of any suitable material.

What we claim, and desire to secure by Letters Patent, is—

1. The combination, with a filler, an intermittently-moved plate having holes to receive 85 the material from the filler, the compressing plungers mounted in guides upon opposite sides of the plate, and the slide F, which moves the plate, of the main driving-shaft carrying the eccentrics h h and the peripherally-grooved 90 drum E, the levers H² H², the rod H⁴ between one of the said eccentrics and one of the levers, and the horizontally-pivoted lever D, engaging with the groove in the drum E and connected with the slide F, substantially as described. 95

2. The combination, with a filler, an intermittently-moved plate having holes to receive the material from the filler, the compressing plungers mounted in guides upon opposite sides of the plate, and the slide F, which moves the plate, of the main driving-shaft carrying the eccentrics h h and J and the peripherally-grooved drum E, the levers H² H², operated by the eccentrics h and connected to reciprocate the plungers, the horizontally-pivoted lever D, operated by the drum E and connected to move the slide, the lever J', operated by the eccentric J, and the plungers which remove the material from the holes in the plate and clean the same, operated by the lever J', 105 substantially as described.

3. In a drug-compressing machine, the combination of an adjustable filler having a discharge-orifice, a rotating disk in contact with the filler and provided with a series of holes, 110 in which the drug is compressed, arranged to move past and register with the discharge-orifice in the filler, an adjusting-screw for changing the relations of the discharge-orifice to the holes in the rotating disk, and means 115 for compressing the drug in said holes, substantially as described.

4. The combination, with the filler, an intermittently-moved plate having holes to receive the material from the filler, the compressing-plungers mounted in guides upon opposite sides of the plate, and the slide which moves the plate, of the main driving-shaft carrying the eccentrics h h and J, the drum E, and the pulley B², all arranged side by side, 125 the levers operated by the eccentrics h and connected to reciprocate the plungers, the le-

ver D, operated by the drum E and connected to move the slide, the lever J', operated by the eccentric J, the plungers which remove the material from and clean the holes in the plate, operated by the lever J', the oppositely-revolving stirrers mounted in the filler, the shaft which drives the stirrers, and the band B³, driving the said shaft from the pulley B², substantially as described.

In testimony whereof we have hereunto set 10 our hands in the presence of two subscribing witnesses.
